UNITED STATES PATENT OFFICE.

ADAM C. WILLIAMS, OF RAVENNA, OHIO.

DESIGN FOR A TOY BANK.

SPECIFICATION forming part of Design No. 37,395, dated April 11, 1905.

Application filed February 26, 1904. Serial No. 195,482. Term of patent 14 years.

To all whom it may concern:

Be it known that I, ADAM C. WILLIAMS, a citizen of the United States of America, residing at Ravenna, in the county of Portage and State of Ohio, have invented a new, original, and ornamental Design for a Toy Bank, of which the following is a specification, reference being had to the accompanying drawings, forming part thereof.

In the drawings, Figure 1 is a view in side elevation of a toy bank embodying my ornamental design. Fig. 2 is a top plan of same.

What I claim is—

The ornamental design for a toy bank as shown.

ADAM C. WILLIAMS.
